FREQUENCY-MODULATION DEMODULATOR
SYSTEM

Joseph A. Worcester, Jr., Syracuse, N. Y., assignor to General Electric Company, a corporation of New York

Application April 2, 1948, Serial No. 18,645

2 Claims. (Cl. 250—27)

1

The present invention relates to demodulators of frequency modulated wave energy, and more particularly to such demodulators utilizing electron beam tubes.

It is an object of this invention to provide an improved detector for demodulating frequency modulated wave energy, this detector being insensitive to any amplitude variations which may be incidentally modulated on the wave energy.

A further object of this invention is to provide such a detector as used in frequency modulation receiving systems the operation of which is such that the need for amplitude limiter stages, inter-station noise-muting circuits, and the like is obviated.

A still further object of this invention is to provide a frequency modulation receiving system in which the function of limiting and demodulating are performed in a single tube, precluding the need for separate limiter stages, frequency discriminator transformers and the like.

Yet a further object of this invention is to provide an electron beam tube for use in frequency modulation receiving systems and the like, wherein the output of the final intermediate frequency stage in such a system may be coupled directly to this tube, and audio frequency potentials may be recovered from the output thereof, in response to frequency modulated signals, and wherein the output is substantially zero for amplitude modulated signals.

Still another object of this invention is to provide a highly efficient and highly stable frequency modulation receiving system which is relatively simple and economical to construct and in which the necessary component parts and circuits are reduced to a minimum.

The features of this invention which are believed to be new are set forth with particularity in the appended claims. The invention itself, however, together with further objects and advantages thereof may best be understood by reference to the accompanying drawing, in which, Fig. 1 shows one embodiment of the invention, Fig. 2 shows a portion of the system of Fig. 1 useful for describing the operation thereof, and Fig. 3 shows a preferred modification of the invention, incorporating a beam centering arrangement.

It has long been desirable to evolve a system which combines the frequency modulation functions of limiting and detecting in a single tube in order to eliminate the limiter stage, the frequency discriminator transformer, detecting diodes, and the multiplicity of small components.

associated with conventional frequency modulation receiving systems. Such a system is shown in Fig. 1.

Referring now to Fig. 1, an electron beam tube, 5 constructed in accordance with the present invention, is represented generally as 1. The present tube is similar fundamentally to a conventional cathode-ray tube, in that focusing electrodes 2, 3 and 4, connected to suitable taps on a source of unidirectional potential 5, are used to focus a beam of electrons into a beam of extremely small cross-sectional area. This beam of electrons is produced by a usual cathode 6 connected to the negative terminal of source 5 and heated by heating elements 7. The tube 1 also contains conventional horizontal and vertical deflecting electrodes 8, 8' and 9, 9' to deflect the beam, in a manner to be described. The difference between the present tube and the conventional cathode-ray tube lies in that a special plate construction replaces the cylindrical high potential anode and fluorescent screen of the usual tube. This plate construction includes metallic circular disk quadrants 10 and 11 which are connected together, and to a source of unidirectional potential B+ through load resistor 12. Load resistor 12 is bypassed for intermediate frequencies by integrating capacitor 13, and connected to terminals 14 through capacitor 15. The above-mentioned plate construction also includes a further circular disk-like plate 16 which is located a short distance behind sections 10 and 11 with respect to the electron beam. The plate 16 is connected directly to unidirectional source B+ and acts as a collector for the electron beam when it is deflected other than on the segments 10 and 11.

The final intermediate frequency amplifier stage of the frequency modulation radio receiving system is shown generally as 17. The stages of this system, preceding the final intermediate frequency stage, are conventional and may take any known form, and a detailed description of these stages is believed to be unnecessary. Stage 17 includes an electron device 18 connected in the usual manner. The cathode of device 18 is connected to ground through biasing resistor 19 bypassed by capacitor 20. Control electrode 21 is coupled to the preceding stage in the usual manner, screen electrode 22 is connected to unidirectional source B+ through resistor 23 and to ground through a capacitor 24, and suppressor electrode 25 is connected directly to the cathode of device 18. The anode 26 is coupled to unidirectional source B+ through the primary wind-

ing 27 of intermediate frequency transformer 28, the primary winding 27 being tuned to the intermediate frequency of the system by variable capacitor 29. The primary winding 27 is coupled to the horizontal deflection plates 8 and 8' through capacitors 30 and 31, and secondary winding 32 of transformer 28, tuned to the intermediate frequency by capacitor 33, is coupled to the vertical deflection plates 9 and 9' through capacitors 34 and 35.

Referring now to Fig. 2, there is shown a view of the sector plates 10 and 11 and plate 16 taken from the cathode end of the electron beam tube 1 of Fig. 1. At the resonant frequency of the intermediate frequency transformer 28 of Fig. 1, a 90° phase angle exists between the primary and secondary potentials thereof, which causes the electron beam to trace a circular pattern such as the dotted figure 1'-2'-3'-4'. It can be seen that during the time interval of each revolution of the electron beam, the beam contacts the circular plate 16 for one-half of this time interval and the sectors 10 and 11 for the other half. When the frequency of the received signal is deviated from the resonant frequency of the circuit, the circular pattern changes to an ellipse tending towards the line 1'-3' for a frequency deviation in one direction, and towards the line 2'-4' for a frequency deviation in the opposite direction. In the former case the beam falls entirely on the collector plate 16, and in the latter case entirely on the segments 10 and 11, except for the small gap at the center. It can then be seen that the average beam current varies substantially from zero at one extreme of frequency deviation of a received signal to a maximum at the other extreme of this frequency deviation. The beam current has a value midway between zero and the maximum, when the frequency of the received signal corresponds to the resonant frequency of the intermediate frequency circuit. Hence, integrating capacitor 13 removes the intermediate frequency component, and an audio potential, varying in accordance with the frequency deviation of the applied signal, may be derived across the terminals 14.

The present system is responsive solely to frequency modulated signals, and it can be shown that the system is insensitive to amplitude modulated signals. Considering the case where an applied signal has a frequency corresponding to the resonant frequency of the intermediate frequency transformer 28, a circular pattern is obtained on the electron tube plate construction. It is evident that amplitude changes in the applied signal merely change the diameter of the circular figure 1'-2'-3'-4' and hence do not effect the output of the device, as the beam contacts the segments 10 and 11 for one-half of the total time interval, regardless of the size of the circular figure. The same situation exists during the various off-tune conditions, as merely the size of the pattern alone changes, and the shape remains the same and hence the integrating current through load resistor 12 is unchanged.

The coupling between the intermediate frequency transformer 28 and the deflecting electrodes 8 and 9 of Fig. 1 may be double-ended, as shown in that figure, or on the other hand, this connection may be of the single-ended variety with one horizontal and one vertical deflecting electrode operating at zero intermediate frequency potential, such an arrangement being shown in Fig. 3.

Referring now to Fig. 3 in detail, there is shown

the final intermediate frequency stage 17 of a frequency modulation receiving system similar to Fig. 1. The output transformer 28 of this stage has one side of its primary winding 27 connected to a source of unidirectional potential and the other side thereof coupled to the vertical deflection electrode 9 through capacitor 30. The secondary winding 32 of transformer 28 has one side connected to ground and the other coupled to the horizontal deflecting electrode 8 through capacitor 34.

In other respects the circuit of Fig. 3 is similar to that of Fig. 1, with the exception that means are provided for accurately centering the electron beam when no deflecting potential is impressed on the horizontal and vertical deflecting electrodes. The centering of the beam is accomplished by dividing the collector plate into two semi-circular segments 16 and 16' these segments being connected to the unidirectional source B+ through resistors 36 and 37. The potential drop appearing across resistors 36 and 37 is applied to the horizontal deflecting electrodes 8' and 8 respectively through resistors 38 and 39, in conjunction with the inherent circuit capacitance, preventing intermediate frequencies from being applied to the deflecting electrodes 8 and 8'. Hence, when the beam is inaccurately centered and falls, for example, on plate 16', current flows through resistor 37 causing a potential to be applied to deflecting electrode 8, which consequently deflects the beam in a compensating direction. Likewise, segments 10 and 11 are connected to the audio load resistor 12 through respective compensating resistors 40 and 41, the potential appearing across these resistors being applied respectively to the vertical deflecting electrodes 9' and 9 through resistors 42 and 43. The combined action of these compensating potentials causes the electron beam to seek its central position. The above-described compensating action also prevents any tendencies of the beam to be deflected by extraneous hum potentials and the like.

The beam centering circuits per se are more particularly described and claimed in the pending application of Robert B. Dome, Serial No. 4,810, filed January 28, 1948, for "Deflection Limiter" and assigned to the same assignee as the present invention.

This invention therefore provides an improved frequency modulation demodulator which uses an electron beam tube of special construction, and when utilized in conjunction with a frequency modulation receiving system, renders the need for amplitude limiter stages, frequency discriminator transformers and other associated components, unnecessary.

While certain specific embodiments have been shown and described, it will of course be understood that various modifications may be made without departing from the invention. The appended claims are therefore intended to cover any such modifications within the true spirit and scope of the invention.

What I claim as new and desire to secure by Letters Patent of the United States is:

1. A frequency modulation demodulator system comprising a source of signals frequency modulated about a center carrier frequency, an electron beam tube and an output circuit, said electron beam tube including a source of electrons, beam focusing means, horizontal and vertical beam deflecting means, and beam collecting means, said beam collecting means comprising a

first pair of diametrically-opposed sector members, a second pair of diametrically-disposed sector members spaced from said first pair and not more than partially shielded thereby, means for impressing said signals across said deflecting means with the phase of said center frequency impressed on said vertical deflecting means displaced by 90° from the center frequency impressed on said horizontal means, a first and second resistance means for coupling respectively the opposing sector members of said first and second pairs, means for coupling said output circuit to said first and second resistance means respectively, means for deriving audio signals from said output circuit in response to said frequency modulated signals, means for impressing a positive voltage with respect to said electron source to intermediate points of said first and said second resistance means respectively, and direct current connections for applying potentials developed across said first resistance to said horizontal beam deflecting means and for applying potentials developed across the other of said resistance means to said vertical beam deflecting means to center said beam.

2. A frequency modulation demodulator system comprising a source of signals frequency modulated about a center carrier frequency, an electron beam tube and an output circuit, said electron beam tube including a source of electrons, beam focusing means, horizontal and vertical beam deflecting means, and beam collecting means, said beam collecting means comprising a first pair of diametrically-opposed sector members, a second pair of diametrically-disposed sector members spaced from said first pair and not more than partially shielded thereby, means for impressing said signals across said deflecting means with the phase of said center frequency

impressed on said vertical deflecting means displaced by 90° from the center frequency impressed on said horizontal means, said means including a transformer having a primary winding and a secondary winding with one of said windings coupled to said horizontal deflecting means and the other winding coupled to said vertical deflecting means, a first and second resistance means for coupling respectively the opposing sector members of said first and second pairs, means for coupling said output circuit to intermediate points of said first and second resistance means respectively, means for deriving audio signals from said output circuit in response to said frequency modulated signals, means for impressing a positive voltage with respect to said electron source to said intermediate points on said first and said second resistance means respectively, and direct current connections for applying potentials developed across said first resistance to said horizontal beam deflecting means and for applying potentials developed across the other of said resistance means to said vertical beam deflecting means to center said beam.
